UNITED STATES PATENT OFFICE.

SIMS LEVER, OF SYDNEY, NEW SOUTH WALES, AUSTRALIA.

NECKBAND OF SHIRTS, BLOUSES, AND THE LIKE.

1,076,381.

Specification of Letters Patent.

Patented Oct. 21, 1913.

Application filed October 24, 1910. Serial No. 588,648.

To all whom it may concern:

Be it known that I, SIMS LEVER, a subject of the King of Great Britain, residing at No. 229 Macquarie street, Sydney, in the State of New South Wales and Commonwealth of Australia, manufacturer, have invented a new and useful Improvement in Neckbands of Shirts, Blouses, and the like, of which the following is a specification.

This invention has been specially devised in order to provide a neck band for shirts blouses and like wearing apparel so that it will within limits conform to the size of the collar worn on said garments and will also allow more freedom to the neck of the wearer than bands as hitherto constructed.

According to this invention the neck band instead of being made in one piece is made in at least three sections attached to the garment and preferably overlapping one another though one or both ends of each section might telescope in the adjacent ends of contiguous sections. The back and front stud holes or buttons are positioned in or on the neck band and the opening of the garment is made either at the front or back as ordinarily. But in order that a practical application of this invention may be readily understood the same will now be described with reference to the drawings accompanying and forming part of this complete specification in which in perspective views various modifications of application of the invention are shown.

Figure 1 shows the preferred construction of divided overlapped form of neck band, Fig. 2 shows a modified form of division, Fig. 3 shows a modified or open nicked form, Fig. 4 a modified or closed nicked form, Fig. 5 shows a telescopic division, Fig. 6 a tongue and loop division, Fig. 7 a tag and slot overlap division and Fig. 8 an overlapped double slots division.

In the make shown in Fig. 1 the sections 9, 10 and 11 are sewn to the garment 12 with the ends of the back section 11 overlapping the ends of the front sections 9 and 10 preferably on the outside thereof though such overlapping could take place on the inside.

In the band of Fig. 2 the overlapping portion of the end of the back section 11 is left free from the garment 12 so as to give said section more freedom to retire upon receiving pressure from the neck of the wearer. If the ends of the back section 11 overlap on

the inside of the front section the overlapping portion of said front sections should be left free. The overlapping portions of both sections might be left free so that either portion can be folded inside or overlap on the outside as desired.

Fig. 3 shows the construction with a V shaped nick or cut 13 in the band and of which there may be more than one and which opening can be made by cutting it from a whole neck band. Though such opening may be made by attaching sections as 10 and 11 with their ends diagonally cut so that a V shaped or other opening is left.

Fig. 4 shows an opening as in Fig. 3 having the edges or adjacent ends of the sections as 10 and 11 joined by a soft material 14.

Fig. 5 shows the end of one section as 10 cut so as to form a tongue 15 telescoping in the split or open adjacent end 16 of the other section as 11.

Fig. 6 shows the end of one section as 11 having a loop or guide 17 for the reception of the tongue 15 on the end of the adjacent section as 10.

Fig. 7 shows one end of a section as 10 having a tag 18 adapted to take through and slide in a slot 19 in the end of the adjacent section as 11.

Fig. 8 shows each overlapping end of contiguous sections as 10 and 11 having a slot 20 to carry a flat headed stud 21.

In all the constructions or modifications above described enlargement and contraction of the length or size of the neck band is provided for by the movement within limits of the various sections of said neckband. And so in use the neck band will contract or decrease in diameter or will extend or increase in diameter within limits to varying sizes of collars and by reason of sections moving when the neck of the wearer bends to either side or backwardly will allow of more freedom to the neck of the wearer than have neck bands as hitherto constructed as will readily be understood.

Having now fully described and ascertained my said invention and the manner in which it is to be performed I declare that what I claim is:

In a shirt, a body portion having a substantially vertical line of closure, and a neckband secured to said body, said neckband comprising at least three distinct

strips disposed to overlap at their respective extremities, one of said strips extending around one side of the neck opening of the body portion from said line of closure to a point substantially above one shoulder portion of the garment and another of said strips similarly extending around the other side of said opening to a corresponding point above the other shoulder of said garment, the respective overlapped ends of said

strips above said shoulders being free to slide over each other.

In testimony whereof I have signed my name to this specification in the presence of two subscribing witnesses.

SIMS LEVER.
